EDWARD J. KEATING, OF BRIDGEPORT, CONNECTICUT.

WINDOW-SASH LOCK.

1,147,175.

Specification of Letters Patent.

Patented July 20, 1915.

Application filed May 11, 1915. Serial No. 27,299.

To all whom it may concern:

Be it known that I, EDWARD J. KEATING, citizen of the United States, residing at Bridgeport, in the county of Fairfield and State of Connecticut, have invented certain new and useful Improvements in Window-Sash Locks; and I do hereby declare the following to be a full, clear, and exact description of the invention, such as will enable others skilled in the art to which it appertains to make and use the same.

My invention relates to window sash locks, and it consists in certain details of construction set forth in the following specification.

15 Referring to the drawings wherein Figure 1 represents a sectional view of the two meeting rails and a part of the locking device on line 1—1 of Fig. 2; Fig. 2 is an upper plan view of the locking device and 20 a broken view of the meeting rails; Fig. 3 is a broken sectional view of the inside meeting rail and a sectional view of the locking device on line 3—3 of Fig. 1, also broken view of the locking bolt; Fig. 4 is a broken 25 side elevation of the inside meeting rail and locking bolt in open position; Fig. 5 is an enlarged broken view partly in section of the locking device connected with the inside meeting rail; Fig. 6 is an enlarged detail 30 view of the table part of the tilting frame of the locking device; Fig. 7 is an enlarged broken detail view of the support for the table; Fig. 8 is an enlarged view 35 partly in section of locking device connected with the inside meeting rail in locked position, broken view of the locking bolt, broken sectional view of part of the box in 40 which the locking device is located, and broken view of the tilting frame retaining 45 spring; Fig. 9 is an enlarged detail view of the key; and Fig. 10 is an enlarged broken 50 sectional view of the housing and box connected with the inside meeting rail.

The outer meeting rail 1 carries the over- 45 hanging locking bolt 2 and housing 3. This housing has the extension 4 resting on the surface of the rail, and the right angle bend 5 which lies against the inside face of the rail and is secured thereagainst by the 50 screws 6. The housing 3 has the opening 7 to form an upper bearing for the locking bolt, while its lower end 8 has a bearing in the hole 9 of the rail. 10 is a spring under- 55 lying said bolt adapted to exert an upward pressure thereagainst.

11 is an enlarged portion of the bolt whose

diameter is greater than the diameter of the hole 7 of the housing to form a check for the upward travel of the bolt when the same is unlocked.

60 The inside meeting rail 12 carries the metal box 13 in which the locking mechanism, presently to be described, is located. The housing 14 has the square opening 15 adapted to receive the square end 16 of the locking bolt. This housing 14 has the extension 17 resting on the upper surface of the rail, with the right angle bend 18 lying against the outer face of the rail and is held thereagainst by the retaining screws 19. 70 The inner portion of the housing 14 is locked to the box 13 as shown more clearly in Fig. 10, wherein the inwardly bent portion 20 of the housing is inserted in the opening 21 of the box 13. The purpose of thus attaching 75 the housings to the meeting faces of the rails is to prevent the housings from being removed from the outside, as would be the case were they attached to the upper face of the rails.

80 22 is a frame—see also Fig. 8—whose upper bar 23 is adapted to be engaged by the catch portion 24 of the locking bolt. This frame is secured to the rod 25, and this rod is journaled in the sides of the box 13, shown 85 at Fig. 1.

85 26 is a table or support carried by the frame 22 whose inner end engages the platform 27 to limit the inward movement of the tilting frame 22 under the impulse of the 90 spring 28. This platform 27 has the side extensions 29 which are secured to the sides of the box 13.

95 30 and 31 are two safety locking levers journaled—see also Fig. 5—on the rod 32 secured to the sides of the tilting frame 22. The horizontal portion of these levers rest in the grooves 33—Fig. 6—of the support 26 to keep them separated. The curved portions 30^a and 31^a of the levers overhang the 100 top bar 23 of the tilting frame—Fig. 5—when the locking bolt is withdrawn from the housing of the inside meeting rail, as shown in Fig. 5. The opposite end of these levers is provided with a retaining hook portion, one, 34, being shown in Figs. 3 and 8, which hook portion is adapted to engage the lip 35 for the purpose presently to be explained.

105 110 The operation of the device is as follows: The locking bolt is swung around until its squared catch end 16 is directly over the

opening in the housing 14, when a downward pressure against the spring 10 will enter the free end of the bolt in said housing. In its descent it will first encounter the overhanging curved ends 30^a and 31^a of the levers 30—31 and tilt said levers to disengage their hook portions 34 from the lip 35, and hold them thus disengaged until the bolt has also tilted the frame 22 so that its catch 24 can pass under the bar 23, when the opposite curved ends will enter the opening 36—Figs. 3 and 8—and thus permit the opposite hook ends to reengage the lip 35. The meeting rails are thus securely locked together and in such a manner that it is impossible to tamper with the lock from the outside and withdraw the bolt. The importance of the safety levers is that the bolt cannot be withdrawn until these levers are released.

To unlock the bolt from the inside, the key 37 is used having the bits 38, one adapted to engage each of the levers as follows: The key is inserted in the key hole 39—Fig. 4—until its forward end rests in the hole 40—Fig. 3—located in the opposite side of the box 13. These key bits will pass through the openings 41—Fig. 7—in the platform 27 and engage the underside of the levers 30—31 at about the point shown in Fig. 8. Turning the key toward the left will disengage the levers from the lip 35 and hold them out of engagement therewith until after the bits have engaged the end *a* of the table 26 and tilted the locking frame 22 to disengage said frame from contact with the locking bolt when said bolt is carried out of the housing 14 by the force of the spring 10, and the levers are reengaged to the lip 35 by the springs 42. It is quite evident that the number of levers and bits may be increased if desired.

Having thus described my invention, what I claim is:—

1. A window sash lock comprising an overhanging locking bolt pivotally supported in one of the meeting rails and adapted to have a horizontal movement, a spring to exert an upward pressure on the bolt, a housing embracing a portion of the bolt to serve as a bearing therefor and also to limit its upward movement, the free end of the bolt having a catch, a housing on the other meeting rail having an opening to receive the free end of

the bolt when depressed, a spring actuated 55 tilting frame with which the catch of said bolt is adapted to engage, pivotally supported safety locking levers carried by the frame, and means for locking said levers to prevent tilting of the frame away from its engagement with the locking bolt.

2. A window sash lock comprising an overhanging locking bolt pivotally supported in one of the meeting rails and adapted to have a horizontal movement, said bolt having a 65 catch at its free end, a spring to exert an upward pressure on the bolt, a housing embracing a portion of the bolt to serve both as a bearing for the bolt and also to limit its upward movement, a housing on the other 70 meeting rail having an opening to receive the free end of the bolt, means for locking the bolt, said housings having extensions projecting against the meeting faces of the rails and secured thereto.

3. A window sash lock comprising an overhanging locking bolt pivotally supported in one meeting rail to have a horizontal movement, a spring to exert an upward tension on the bolt, means for limiting its upward movement, the free end of the lever having a catch, and a box inserted in the other meeting rail carrying locking means adapted to be engaged by the free end of the bolt.

4. The combination with the meeting rails 85 of a window of an overhanging locking bolt adapted to have both a horizontal and vertical movement carried by one of said rails, locking mechanism located in the other rail comprising a spring actuated tilting member, a support therefor to limit the action of the spring, spring actuated and pivotally supported safety locking levers carried by said tilting member, a housing having an 90 opening, a portion of the locking members 95 projecting within said opening, the free end of the locking bolt having locking means, said bolt adapted to be depressed to enter its free end within said opening to first contact with the locking levers and temporarily release the same and then actuate the tilting member and engage therewith.

In testimony whereof I affix my signature in presence of two witnesses.
